SOIL MOISTURE METER

Harry A. Wayne, 4120 W. Greenwood, Skokie, Ill.

Filed Nov. 27, 1959, Ser. No. 58,473

Term of patent 14 years

(Cl. D52—6)

Figure 1 is a perspective view of a soil moisture meter, showing my new design;

Figure 2 is a front elevational view thereof;

Figure 3 is a rear elevational view thereof;

Figure 4 is a side elevational view thereof;

Figure 5 is a top plan view; and

Figure 6 is a bottom view thereof.

The undisclosed side of the soil moisture meter is substantially the same in appearance as the side shown.

I claim:

The ornamental design for a soil moisture meter, substantially as shown and described.
